UNITED STATES PATENT OFFICE

147,421

DESIGN FOR A GAME BOARD

Freeman Sawyer, Au Sable Forks, N. Y.

Application May 20, 1946, Serial No. 129,877

Term of patent 3½ years

(Cl. D34—5)

To all whom it may concern:

Be it known that I, Freeman Sawyer, a citizen of the United States, residing at Au Sable Forks, in the county of Essex and State of New York, have invented a new, original, and ornamental Design for a Game Board, of which the following is a specification, reference being had to the accompanying drawing, forming part thereof.

I claim:

The ornamental design for a game board, as shown.

FREEMAN SAWYER.
